UNITED STATES PATENT OFFICE.

HUGH K. MOORE AND ROBERT B. WOLF, OF BERLIN, NEW HAMPSHIRE.

RECLAIMING WASTE PRODUCTS IN THE MANUFACTURE OF SULFITE FIBER.

1,110,454.

Specification of Letters Patent.

Patented Sept. 15, 1914.

Application filed December 30, 1913. Serial No. 809,525.

To all whom it may concern:

Be it known that we, HUGH K. MOORE and ROBERT B. WOLF, citizens of the United States, and residents of Berlin, in the county of Coos and State of New Hampshire, have invented certain new and useful Improvements in Reclaiming Waste Products in the Manufacture of Sulfite Fiber, of which the following is a specification.

10 This invention has relation to the reclamation of waste products in the manufacture of sulfite fiber, and more particularly to the recovery of the sulfur dioxid which, heretofore in actual practice, has escaped 15 from the blow pit after the cooked charge has been delivered thereto from the digester.

In our previous application Serial No. 590,158, filed November 1, 1910, we have 20 illustrated conventionally an apparatus for and described a process of recovering sulfur dioxid by bringing the vapors from the blow pit into contact with the chilled surfaces of a surface condenser, and condensing 25 them, and then separating the sulfur dioxid from the other gases by absorption in a suitable absorber.

In order to prevent the loss of sulfur dioxid, it is desirable that the products of 30 condensation should be kept as near the boiling point as possible to prevent the absorption thereby of the sulfur dioxid. Further, to secure a greater strength of acid solution in the absorber, it is necessary to 35 eliminate the presence of air in the apparatus during the "blow." We accomplish these results by means which will be subsequently described herein.

On the drawing, in Figure 1 an apparatus 40 is conventionally shown for carrying out our invention. Fig. 2 shows a section through the condenser.

The digester is illustrated at 1 and is of the type used in the manufacture of sulfite fiber. In it are placed the chips and the acid (calcium bisulfite and more or less free sulfurous acid), and, after the neck is sealed, steam is injected into the digester to bring 45 the contents thereof to the proper temperature. If desired, sulfur dioxid may be injected into the digester in accordance with our application Serial No. 541,246, filed February 1, 1910. After the wood has been 50 cooked at the proper temperature for the proper length of time and the cellulose fibers

have been freed from their cementing materials, the contents of the digester are blown in the usual way through the pipe 2 into a blow pit conventionally illustrated at 3, which is constructed with the usual false bottom for permitting the escape of the waste liquors. As usual, the interior of the blow pit is at slightly less atmospheric pressure. Hence, when the contents of the digester of ordinary size are discharged into the blow pit at a steam pressure of say 45 to 75 pounds per square inch (not including the pressure due to the static head), from 18,000 to 20,000 pounds of steam are liberated in the blow pit from the discharged water. The temperature of the contents of the digester varies from 250° F. to 320° F., and, as soon as the materials reach the blow pit, vapors arise therefrom and are conducted away through a vomit stack 4. Heretofore, in actual practice, these stacks have always opened into the atmosphere into which the rising vapors escape and become dissipated. In addition to the vapors, there has been an escape of a certain amount of free sulfur dioxid which was not utilized in the cooking operation. The escape of this free sulfur dioxid is a serious menace to vegetation and is highly objectionable on account of the odor.

In accordance with our process, the vomit stack is closed to the atmosphere during the blow, and the vapors and gases are conducted to a surface condenser conventionally illustrated in Fig. 1 at 5. This surface condenser may be of any suitable or desired type. Preferably, as shown in Fig. 2, it is of the horizontal type and is provided with diaphragms 6, 6 forming compartments 7, 8 and 9, the compartments 7 and 8 communicating through tubes 10 passed through the chamber 9. Partitions 11 divide the chambers 7 and 8 as shown, so that the cooling medium takes a sinuous path through the condenser. As shown in Fig. 1, the vomit stack discharges into the lower extension of compartment 9 through conduit 15, and the gases and vapors are caused to circulate upwardly and around the tubes. Cold water or any other suitable cooling medium is injected through the pipe 12 to the chamber 7, and passing through the tubes is discharged through the circulating pipe 13. The vapors entering the condenser from the vomit stack are condensed and pass from the trap

16 through a pipe 17 to a receptacle 18 from which they may be drawn by the valved discharge pipe 26. Ordinarily we employ water as the cooling medium at its seasonable temperature, although in lieu thereof some other chilled cooling medium may be utilized, or the water itself may be cooled prior to its admission to the condenser.

The effect of condensation of the vapors 10 is to reduce to liquid form the water vapor and such compounds as wood alcohol, benzaldehyde, acetone, acetic acid, and other vapors which would condense at or slightly above the temperature of the cooling medium, the quantities, amounts and character of these compounds depending more or less upon the methods, temperature, etc., used in cooking as well as the nature of the materials cooked. The application of the 15 principle of recovering these compounds by condensing vapors arising from the blow pit, while herein described as applying to the sulfite process, may be applied to any other process in which free gases are discharged.

The condensation of the water vapor to water permits the absorption by the condensed water of only a relatively small proportion of the free sulfur dioxide gas which 20 escapes with the vapor, and consequently the great portion of free sulfur dioxide which is uncondensed passes through the condenser and is conducted away therefrom by means of the pipe 14 to an absorbing apparatus, 25 which is illustrated as comprising a tower 19 containing limestone. In the upper end of the tower is shown a sprinkler head 20 through which water is sprinkled into the tower. In the passage of the sulfur dioxide 30 through the tower, it reacts with the lime and is finally discharged through the pipe 21 as a solution of calcium bisulfite and free sulfuric acid. The effluent from the tower is collected in a tank 22 from which it 35 may be drawn by a valved pipe 23. A vacuum pump 24 is connected to the upper end of the tower. In the conduit leading to the vacuum pump, I have indicated a regulator check valve 25 of any suitable construction, which will open when the vacuum 40 is too great to avoid damage to the blow pit.

The product of condensation, which is collected in the tank 14 or the tank 18 as the case may be, may be neutralized with lime. This has the effect of precipitating the sulfur dioxide in the form of calcium monosulfide ($CaSO_3$) which is removed by passing the materials through a filter press, 45 leaving the filtrate practically clear and neutral. The filtrate contains acetic acid in the form of a lime or other salt, methyl alcohol, benzaldehyde, acetone and other organic acid salts and compounds which may be separated and removed by any well known

process, such as evaporation, fractional distillation and precipitation by various reagents. The contents of the tank 22 may be used in the digesters in cooking the wood.

The vomit stack 4 at a suitable point has 70 a luted cover 26 partially balanced by a weight 27 so that the stack may be opened to the atmosphere. Immediately prior to the blow, steam is injected into the pit 3 through a valved steam pipe 28 for the 75 purpose of completely filling the pit and the stack with steam and thereby forcing therefrom any air which is contained therein. Then the cover or cap 26 is closed, the supply of steam through the pipe 28 is cut 80 off, the vacuum pump 24 is started, and then the contents of the digester are discharged into the blow pit. The steam in the blow pit, prior to the admission of the contents of the digester, rapidly condenses and there 85 is substantially no pressure above atmospheric pressure in the blow pit. The rising vapors pass from the vomit stack through the conduit 15 into the condenser 5 and are condensed as explained.

The present invention provides for completely reclaiming the sulfur dioxide which has heretofore been lost in the operation of blowing the digesters into the blow pits. In addition to reclaiming the sulfur dioxide 95 so that it may be again utilized, the present invention provides for reclaiming and utilizing various other valuable products, such as methyl alcohol, benzaldehyde, acetone, acetic acid and other organic acids and compounds.

We have stated that a small proportion of sulfur dioxide is absorbed by the water of condensation in the condenser. Preferably, therefore, the water of condensation is maintained at a temperature but slightly less than the boiling point so as to limit the absorption thereby of the free sulfur dioxide. But utilizing the horizontal surface condensing the vapors from the blow pit, the 105 only water which can absorb the sulfur dioxide is that which has been condensed from the steam coming from the blow pit, and the water being brought out near the boiling point, it contains a minimum amount 110 of gas. Consequently the greater volume of free gas will not be absorbed by the water but will pass on to the absorbing tank or tower. Furthermore, by the employment of a surface condenser, the water, which is 115 used as the cooling medium and which is delivered from the condenser, is in a clean heated condition and may be utilized for a variety of purposes for which it could not be used if it had been previously employed 120 in the direct condensation of the vapors by contact therewith, because, in the latter case, it would have absorbed a portion of the sulfur dioxide and other products from the blow pit.

In the form of condenser shown, the products of condensation dropping from the tubes are met by the incoming vapors and are heated thereby nearly to the boiling point so as to effect the liberation of sulfur dioxid absorbed thereby.

It will be understood that the condenser may be connected to a series of blow pits to receive the vapor therefrom.

10 We have herein stated that we may treat the product of condensation in the tank 18 with lime to reclaim the sulfur dioxid absorbed therein. On the other hand, however, we may first subject the product of 15 condensation to a vacuum for the purpose of liberating the sulfur dioxid which may be condensed or absorbed in any suitable manner. The remaining product of condensation, which contains acetic acid, may be 20 brought into the presence of metallic lead for the purpose of producing lead acetate, after which the remaining products may be recovered as previously indicated.

We have herein stated that, prior to the 25 blow, the pit and vomit stack are swept clean of air by the injection of steam. This is a feature of great advantage as it relieves the vacuum pumps of the necessity of exhausting the air from the pit and stack, 30 and makes it possible to use a smaller vacuum pump than would otherwise be necessary on account of the presence of inert gases. Further, by eliminating the inert 35 gases, a smaller absorption apparatus may be used. Because of the absence of air, a commercial or usable acid may be made in the absorption apparatus, since the effects of partial pressures are obviated. Furthermore, owing to the absence of air, an acid 40 solution is obtained in which the portion of free sulfurous acid is greatly increased, and, in addition, there is no oxidation of the sulfur dioxid to trioxid.

What we claim is:

1. The herein described process of recovering sulfur dioxid, which consists in removing the air from a blow pit, discharging the contents of a digester into said blow pit, separating and recovering the pulp, condensing by surface condensation the vapors arising from said blow pit, and recovering the sulfur dioxid. 45

2. The herein described process of recovering sulfur dioxid, which consists in filling a blow pit with steam to remove the air 50 therefrom, discharging the contents of a pulp digester into the steam-filled blow pit, condensing by surface condensation the vapors arising from the blow pit, and thereby separating them from the sulfur dioxid, and 55 recovering the sulfur dioxid.

3. The herein described process of recovering sulfur dioxid, which consists in first filling an open blow pit with steam to remove the air therefrom, then closing the 60 pit and connecting the same with an air pump, then discharging the contents of a pulp digester into said pit, and condensing the vapors rising from the blow pit, and recovering the uncondensed sulfur dioxid. 65

4. The combination with a digester and a blow pit, of a vomit stack leading from the blow pit and having a removable cap, a condenser connected to the vomit stack, and means for filling the blow pit with steam. 70

In testimony whereof we have affixed our signatures in presence of two witnesses.
